D. A. SULLIVAN

FIREPROOF BUILDING CONSTRUCTION

Filed May 31, 1923

UNITED STATES PATENT OFFICE.

DANIEL A. SULLIVAN, OF BRONX, NEW YORK.

FIREPROOF BUILDING CONSTRUCTION.

Application filed May 31, 1923. Serial No. 642,439.

To all whom it may concern:

Be it known that I, DANIEL A. SULLIVAN, a citizen of the United States, and residing at Bronx, in the county of Bronx and State of New York, have invented certain new and useful Improvements in Fireproof Building Constructions, of which the following is a specification, such as will enable those skilled in the art to which it applies to make and use the same.

This invention relates to improvements in building constructions and particularly to a new method of constructing buildings of various kinds and classes to render the same fireproof and more particularly to confining a fire to a predetermined room or compartment in a building and also to so construct the walls, floors and ceilings of a building, as well as the framework of the building to prevent the collapsing of the floors, walls or ceilings thereof as well as the framework in the event of a fire in a predetermined room or compartment in a building, and the object of the invention is to provide a building of the class specified the walls, floors and ceilings of which as well as the doors and the like are provided with intercommunicating spaces formed by inner and outer facings in the construction of such walls, floors, ceilings and the like, and further to the provision of means for introducing water into said spaces and whereby the water introduced into said spaces will rise under heat, and by reason of filling such spaces, to the ceiling or roof structure of a building and be discharged onto and over the roof; a further object being to provide means for confining the water to the spaces within the walls, floor, ceiling or roof as well as the doors of a predetermined room or compartment of a building in which a predetermined fire is located; and a further object being to provide automatically actuated means for controlling the discharge of water into such spaces; and with these and other objects in view the invention consists in a building construction of the class and for the purpose specified which is simple in construction, efficient in use and which is constructed as hereinafter described and claimed.

The invention is fully disclosed in the following specification, of which the accompanying drawing forms a part, in which the separate parts of my improvement are

designated by suitable reference characters in each of the views, and in which:—

Fig. 1 is a perspective diagrammatic sectional view of a building or part of a building made according to my invention; 60

Fig. 2 is a sectional detail view on an enlarged scale of a part of the construction shown in Fig. 1; and,

Fig. 3 is a detail view of another part of the construction shown in Fig. 1 on an enlarged scale. 65

In Fig. 1 of the drawing 1 have shown for the purpose of illustrating one use of my invention, the upper structure of a dock or pier, and in said figure 5 represents the 70 floor of the pier, 6 the side walls thereof, 7 the roof construction and 8 partition walls dividing the upper structure of the pier into a plurality of rooms or compartments.

In constructing the floor, walls and roof 75 structure of the pier the floor is made of an upper floor member 5^a and a lower floor member 5^b spaced apart by suitable members 5^c of openwork construction to form a chamber or space 5^d, while the walls 6 are 80 composed of inner members 6^a and outer members 6^b spaced apart by openwork brace members 6^c to form compartments or spaces 6^d which communicate with the compartment or space 5^d. The roof structure 7 is 85 also composed of inner and outer wall members 7^a and 7^b spaced apart by suitable openwork members 7^c to form chambers or spaces 7^d which communicate with the spaces or chambers 6^d, and which also communicate 90

with each other at the peak of the roof structure. The partition walls 8 of the pier structure are composed of two outer wall members 8^a and 8^b and an intermediate wall member 8^c between which and the first named 95 wall members are spaces 8^d and 8^e respectively, and the wall members 8^a and 8^b are spaced from the wall member 8^c by openwork brace members 8^f, and the spaces 8^d and 8^e are in communication with the spaces 5^d, 6^d 100 and 7^d, but the spaces 8^d and 8^e are not in communication, and this is accomplished by extending the wall member 8^c into the spaces 5^d, 6^d and 7^d, this wall is shown entering the spaces 7^d at 8^g in Fig. 1, the reason for this 105 latter construction is to confine the intercommunicating spaces 5^d, 6^d, and 7^d to predetermined rooms or compartments in the entire pier structure.

It will be understood that the partition 110

wall 8 divides the upper pier structure, in the construction shown, into two rooms or compartments 9 and 10, and in the drawing I have shown two doors 11 and 12 in the room or compartment 9, both of these doors being substantially of the same construction and being suspended from and movable longitudinally on guide rails 13, and the doors 11 and 12 are both made hollow or provided with spaces 14, and this space is shown in the door 12, and coupled with the lower end portions of both of the doors on a swiveled mounting are pipes 15 and similar pipes 16 are connected with the lower end portions of the inner wall member 6^a and 8^a respectively, and the pipes 15 and 16 are coupled together by swiveled joints 17 and other pipes 18 are coupled with the upper end portions of the doors 11 and 12 and have swiveled couplings 19 with pipes 20 which are mounted in the inner walls 6^a and 8^a respectively. The above described construction places the chambers or spaces 6^a and 8^a in communication with the chambers or spaces 14 in the doors 11 and 12 at two different points.

At the peak of the roof structure 7 of the pier and arranged to communicate with the spaces 7^d of the separate rooms or compartments 9 and 10, etc., are tubular discharge members 21 having conical caps 22 which prevent the passage of rain water or the like into the spaces of the floor, walls and roof structure and also operate to deflect the water discharged from said spaces onto the outer wall member 7^b of the roof structure, and this water is preferably collected in gutters 23 at the opposite sides of the roof structure, one of which is shown in Fig. 1 and is discharged through a pipe 24 which communicates with the gutter or gutters 23.

The top structure of the pier is reinforced and supported by an external framework construction 25 comprising a plurality of standards 26 joined by longitudinal members 27 and transverse members 28, and the object of this construction is to prevent the direct heat from a fire in a predetermined room or compartment from coming in contact with this frame structure and thus preventing the collapsing of the frame structure of the building or of the upper pier structure as shown in the accompanying drawing.

Mounted centrally and longitudinally of the upper or peaked portion of the roof structure 7 of the pier and extending longitudinally therethrough is a water supply pipe 29 provided at predetermined points preferably within the separate rooms or compartments of a building by the pier structure as shown in the accompanying drawing with laterally and downwardly directed pipes 30, one of which is shown com-

plete in Fig. 1 of the drawing, and these pipes communicate with the spaces 6^a through the walls 6 of the pier at the bottom thereof or adjacent to the floor structure 5 as clearly shown. In the pipes 30 adjacent to their coupling with the pipe 29 are spaced valves 31 as clearly shown in Fig. 2 of the drawing, said valves being normally closed and provided with operating levers 32 having weights 33 at their free ends and normally held in an inoperative position by a fusible coupling 34 suspended from the pipe 29.

My invention will be readily understood from the foregoing description when taken in connection with the accompanying drawing and the following statement. For example let us assume that a fire should start in the room or compartment 9, the fusible connection 34 when subjected to the heat of the fire will be fused thus releasing the weighted levers 32 to move said levers by reason of the weights 33 into position to open the valves 31 thus allowing water from the pipe 29 to pass downwardly into and through the pipes 30 and thus into the spaces 6^a as well as the space 5^a, of the walls and floor structure of the room or compartment 9 and also into the space 8^a of the partition wall 8, this water will then arise by volume, and also by reason of its being heated, into the spaces 7^d and thus out over the roof structure 7 through the discharge 21 enclosing the room or compartment 9. In the aforesaid operation water will also pass into the spaces or chambers 14 of the doors 11 and 12 through the pipes 16 and 15 and out from said spaces through the pipes 18 and 20, and in this way a circulation of water is provided through all of the spaces 5^a, 6^a, 7^d, 8^a and 14 thus operating to keep the partition walls, floor and roof structure of the compartment 9 cool at all times, said spaces operating as water-jackets for the room or compartment 9, and while the fire may destroy or partially destroy the material stored within the specific room or compartment 9 it cannot enter into adjacent rooms or compartments, and it will also be apparent that the water which passes through the spaces in the walls, floor and roof structure as well as the partition walls is confined to the chamber 9 and does not pass into said spaces around or through rooms or compartments of the pier structure and by providing comparatively shallow spaces, for example, approximately one inch from wall member to wall member a great volume of water will not be required. It will be understood, however, that in the event of a large room or compartment a number of the pipes or pairs of pipes 30 may be employed and, if desired, more than one water supply pipe 29 may be employed. I also employ one or more discharge valves

35 which communicate with the lower spaces 5^a and 6^a surrounding the separate rooms or compartments 9 and 10, whereby after water has been introduced into the 5 intercommunicating spaces around the pre-determined room or compartment and perform the desired function and this water supply so introduced is shut-off, the water remaining in these spaces may be drained 10 off and this would especially be the case during winter time or in freezing weather. It will also be apparent that while I have shown a specific method of carrying my invention into effect that I am not necessarily 15 limited to any specific use of my improved building construction as the same may be employed in the construction of independent rooms or compartments, or in the construction 20 of an entire building of any kind or class, and various changes in and modifications of the construction herein shown and described may be made, within the scope of the appended claims, without departing from the spirit of my invention or sacrificing 25 its advantages.

Having fully described my invention, what I claim as new and desire to secure by Letters Patent, is:—

1. A building construction of the class described the floor, walls and ceiling or roof of one or more rooms or compartments of which are provided with intercommunicating spaces, means controlled by a fusible element for automatically introducing water 30 into said spaces, said spaces being formed by inner and outer floor, wall or ceiling members, and the frame work of the building or the room or compartment thereof being located outwardly of the outer floor, wall or 35 ceiling members.

2. A building construction of the class described the floor, walls and ceiling or roof of one or more rooms or compartments of which are provided with intercommunicating 40 spaces, means controlled by a fusible element for automatically introducing water into the lower portion of said spaces, said spaces being formed by inner and outer floor, wall or ceiling members, the framework of 45 the building or the room or compartment thereof being located outwardly of the outer floor, wall or ceiling members, and means for discharging water from the space in said 50 ceiling or roof member.

3. A building construction of the class described the floor, walls and ceiling or roof of one or more rooms or compartments of which are provided with intercommunicating spaces, means controlled by a fusible 55 element for automatically introducing water into the lower portion of said spaces, said spaces being formed by inner and outer floor, wall or ceiling members, the framework of the building or the room or compartment thereof being located outwardly of 60

the outer floor, wall or ceiling members, means for discharging water from the space in said ceiling or roof member, and means for draining water from said spaces.

4. A building construction of the class described the floor, walls and ceiling or roof of one or more rooms or compartments of which are provided with intercommunicating spaces, means controlled by a fusible element for automatically introducing water 70 into the lower portion of said spaces, said spaces being formed by inner and outer floor, wall or ceiling members, the framework of the building or the room or compartment thereof being located outwardly of the outer floor, wall or ceiling members, means for discharging water from the space in said ceiling or roof member, means for draining water from said spaces, the building, or the 75 separate rooms or compartments thereof, being provided with doors having spaces therein, and means for circulating the water introduced into said wall spaces through the spaces in said doors, said last named means involving movably connected pipe elements. 80

5. A pier building structure of the class described comprising a suitable structural framework within which is formed a floor, walls and partition walls and roof structures composed of inner and outer members between which are intercommunicating spaces and said partition walls being so constructed as to divide the building structure into a plurality of rooms or compartments, the intercommunicating spaces of which are subdivided. 95

6. A pier building structure of the class described comprising a suitable structural framework within which is formed a floor, walls and partition walls and roof structures composed of inner and outer members between which are intercommunicating spaces and said partition walls being so constructed as to divide the building structure into a plurality of rooms or compartments, the intercommunicating spaces of which are subdivided, a water supply pipe extending longitudinally of the building, and other pipes communicating with said supply pipe and in communication with the intercommunicating spaces of the floor, walls and roof of the separate compartments. 100

7. A pier building structure of the class described comprising a suitable structural framework within which is formed a floor, walls and partition walls and roof structures composed of inner and outer members between which are intercommunicating spaces and said partition walls being so constructed as to divide the building structure into a plurality of rooms or compartments, the intercommunicating spaces of which are subdivided, a water supply pipe extending longitudinally of the building, other pipes communicating with said supply pipe and in 115

communication with the intercommunicating spaces of the floor, walls and roof of the separate compartments, and valves for controlling the passage of water into said last named pipes.

8. A pier building structure of the class described comprising a suitable structural framework within which is formed a floor, walls and partition walls and roof structures composed of inner and outer members between which are intercommunicating spaces and said partition walls being so constructed as to divide the building structure into a plurality of rooms or compartments, the intercommunicating spaces of which are sub-divided, a water supply pipe extending longitudinally of the building, other pipes communicating with said supply pipe and in communication with the intercommunicating spaces of the floor, walls and roof of the separate compartments, valves for controlling the passage of water into said last named pipes, said valve being normally closed, and means involving a fusible element for retaining said valves in a closed position and whereby when said fusible element is broken the valves are automatically moved into an open position to permit the passage of water into said intercommunicating spaces.

9. A pier building structure of the class described comprising a suitable structural framework within which is formed a floor, walls and partition walls and roof structures composed of inner and outer members between which are intercommunicating spaces and said partition walls being so constructed as to divide the building structure into a plurality of rooms or compartments, the intercommunicating spaces of which are sub-divided, a water supply pipe extending longitudinally of the building, other pipes communicating with said supply pipe and in communication with the intercommunicating spaces of the floor, walls and roof of the separate compartments, valves for controlling the passage of water into said last named pipes, said valves being normally closed, means involving a fusible element for retaining said valves in a closed position and whereby when said fusible element is broken the valves are automatically moved into an open position to permit the passage of water into said intercommunicating spaces, and means for discharging water from the spaces in the roof structure of the separate rooms or compartments.

10. A pier building structure of the class described comprising a suitable structural framework within which is formed a floor, walls and partition walls and roof structures composed of inner and outer members between which are intercommunicating spaces and said partition walls being so constructed as to divide the building structure into a

plurality of rooms or compartments, the intercommunicating spaces of which are sub-divided, a water supply pipe extending longitudinally of the building, other pipes communicating with said supply pipe and in communication with the intercommunicating spaces of the floor, walls and roof of the separate compartments, valves for controlling the passage of water into said last named pipes, said valves being normally closed, means involving a fusible element for retaining said valves in a closed position and whereby when said fusible element is broken the valves are automatically moved into an open position to permit the passage of water into said intercommunicating spaces, means for discharging water from the spaces in the roof structure of the separate rooms or compartments, and means for draining water from said intercommunicating spaces.

11. A pier building structure of the class described comprising a suitable structural framework within which is formed a floor, walls and partition walls and roof structures composed of inner and outer members between which are intercommunicating spaces and said partition walls being so constructed as to divide the building structure into a plurality of rooms or compartments, the intercommunicating spaces of which are sub-divided, a water supply pipe extending longitudinally of the building, other pipes communicating with said supply pipe and in communication with the intercommunicating spaces of the floor, walls and roof of the separate compartments, valves for controlling the passage of water into said last named pipes, said valves being normally closed, means involving a fusible element for retaining said valves in a closed position and whereby when said fusible element is broken the valves are automatically moved into an open position to permit the passage of water into said intercommunicating spaces, means for discharging water from the spaces in the roof structure of the separate rooms or compartments, means for draining water from said intercommunicating spaces, and one or more walls of the separate compartments provided with door openings adapted to be closed by doors having spaces therein.

12. A pier building structure of the class described comprising a suitable structural framework within which is formed a floor, walls and partition walls and roof structures composed of inner and outer members between which are intercommunicating spaces and said partition walls being so constructed as to divide the building structure into a plurality of rooms or compartments, the intercommunicating spaces of which are sub-divided, a water supply pipe extending longitudinally of the building, other pipes

communicating with said supply pipe and in communication with the intercommunicating spaces of the floor, walls and roof of the separate compartments, valves for controlling the passage of water into said last named pipes, said valves being normally closed, means involving a fusible element for retaining said valves in a closed position and whereby when said fusible element is broken the valves are automatically moved into an open position to permit the passage of water into said intercommunicating spaces, means for discharging water from the spaces in the roof structure of the separate rooms or compartments, means for draining water from said intercommunicating spaces, one or more walls of the separate compartments provided with door openings adapted to be closed by doors having spaces therein, and means for circulating water through the spaces in said doors.

13. A pier building structure of the class described comprising a suitable structural framework within which is formed a floor, walls and partition walls and roof structures composed of inner and outer members between which are intercommunicating spaces and said partition walls being so constructed as to divide the building structure into a plurality of rooms or compartments,

the intercommunicating spaces of which are sub-divided, a water supply pipe extending longitudinally of the building, other pipes communicating with said supply pipe and in communication with the intercommunicating spaces of the floor, walls and roof of the separate compartments, valves for controlling the passage of water into said last named pipes, said valves being normally closed, means involving a fusible element for retaining said valves in a closed position and whereby when said fusible element is broken the valves are automatically moved into an open position to permit the passage of water into said intercommunicating spaces, means for discharging water from the spaces in the roof structure of the separate rooms or compartments, means for draining water from said intercommunicating spaces, one or more walls of the separate compartments provided with door openings adapted to be closed by doors having spaces therein, and means for circulating water through the spaces in said doors, said means involving swiveled pipe constructions.

In testimony that I claim the foregoing as my invention I have signed my name this 25th day of May 1928.

DANIEL A. SULLIVAN.
